UNITED STATES PATENT OFFICE

RAGNOR WILHELM MONTÉN, OF SOUTH MELBOURNE, VICTORIA, AUSTRALIA

TIE FOR BALES

Application filed December 17, 1930, Serial No. 503,039, and in Australia September 16, 1930.

This invention relates to an improved tie for wool bales and for analogous purposes and has been devised with the object of providing a tie or fastening device which is particularly applicable for tying wool bales though it can be applied for tying bundles of material together, particularly bundles of soft material such as cotton and the like, although it may be readily applied to the binding of cases, parcels and the like.

The invention, however, will be described particularly for use with wool bales, it being understood that no limitation is to be imposed.

15 A feature of the present invention consists in the employment of a buckle or like connection adapted to take the tension of the tie bands or wires used about the bale and to maintain the said tension until removed by 20 additional means.

An essential feature embodied in the present invention consists in the employment of a specially formed plate incorporating a substantially central depression and opening together with a loop formation at one end, the arrangement being such that when the tie bands or wires are in position they will bear against each other in such a manner that voluntary displacement is totally eliminated.

30 A further advantage occurs with the use of my invention inasmuch as I can effect a great saving in metal as the straps I use need only be of very light section compared with the material at present employed.

35 The invention will now be fully described with reference to the accompanying drawings in which:—

Figure 1 is a perspective view of a wool bale with two of the bale-ties constructed 40 according to the preferred form of my invention secured thereon.

Figure 2 is an enlarged and perspective view of the form of bale-tie shown in Figure 1.

45 Figure 3 is a plan view of the preferred form of connection shown in Figures 1 and 2, and

50 Figure 4 is a view in section showing the positions occupied by the bands when in position about a bale.

Figure 5 is a perspective view of a modified form of connection.

Figure 6 is a plan of a modified form of connection, and

Figure 7 is a central longitudinal section 55 of Figure 6.

Figure 8 is an end view thereof.

Figures 9 and 10 are a further alternative form of connection and longitudinal central section of a further modified form of connection, and

Figures 11, 12 and 13 are views in section, side elevation and end elevation respectively of the connection illustrated in Figure 5.

Figure 14 is a perspective view of a further alternative form of connection.

According to this invention and with particular reference to Figures 1, 2, 3 and 4 which illustrate the preferred embodiment of my invention a plate 5 of suitable gauge 70 material and of convenient length and provided with integral down-turned sides 6 and 7.

Formed at one end of the plate is a depressed portion 8 forming an opening 9, the 75 purpose of which will be hereinafter described.

Formed on the surface 10 of the plate 5 is a depression 11 adapted to provide an opening 12 which is adapted to cooperate 80 with the opening 9.

Passing through the opening 12 is a strap or band of metal 13 which passes around the bale or parcel, the end 15 of the said strap 13 passing through the opening 9 to lie in 85 intimate contact with the strap portion 13.

The strap 13 is then passed around the bale 14 and the other end of the said strap is passed through the slot or opening 12 of the plate 5, said strap being then brought to 90 a position shown more particularly in Figure 4 with its end portion 16 lying against the end portion 15 of the strap 13.

It will be understood that two or any convenient number may be disposed about a bale 95 and in Figure 1 "2" are shown.

When the pressure is released from the bale, the strap ends and the portions engaging the plate connection 5 are brought into very intimate contact and since the bends 100

formed on the straps are substantially acute, the possibilities of voluntary release of tension on the straps 13 is entirely eliminated.

In the alternative construction shown in Figure 5, I provide a connection or buckle incorporating a central opening 17 and two end loops 18 and 19 forming openings as 20 and in this construction the strap 13 is passed through the opening 17 and the end 21 of the said strap is brought upwardly to pass through the openings 20, the pressure on the bale preventing the voluntary release of tension.

The construction illustrated in Figures 6, 7 and 8 is an alternative arrangement which comprises a plate 22 having two openings 23, 24 juxtaposed and provided with loops or depressed portions 25 providing an opening 26 through which the strap will pass as already explained, while Figures 9 and 10 illustrate a further alternative arrangement and incorporates openings 27, 28, loops 29, 30 providing openings 31, 32 and in this construction the bands will be passed through the openings 27, 28 so that their ends pass upwardly through the slots or openings 31, 32, the ends of the straps lying in intimate contact with the binding portion of the said straps.

Figures 11, 12 and 13 are views illustrating in detail the construction shown in Figure 5.

The construction illustrated in Figure 14 discloses a plate 33 having end openings 34 and a central opening 35, the strap 36 being passed through the opening 35 and the end 37 of the said strap 36 passing through one of the openings 34, the strap 36 being then passed about the bale, the opposite end of said strap being also passed through the opening 35, the other end 38 of said strap passing through the other opening 34 so as to lie against the strap 36 and when the pressure is released the straps will be maintained in not only intimate contact but by the sharp bends acquired by the straps in negotiating the metal about the openings prevents the voluntary slackness of the tension of the straps when the pressure is removed from the bale.

In carrying the invention into practical effect, one end of the band or strap 13 is placed through the slot 12, bent back upon itself and then inserted in the slot 9, see particularly Figure 4, the free end of the strap or band 13 being then passed about the bale as 14 and then passed through the slot 12 and bent about the anchored end of the band or strap 13 so that when the pressure is released from the bale 14 the ends of the tie strap or band 13 are pressed against each other and against the main strap 13.

What I claim as my invention and desire to secure by Letters Patent is:—

An improved tie for wool bales and for

analogous purposes characterized by a buckle comprising a plate with downturned sides and having a depressed portion at one end to form an opening and an adjacent opening formed on the said plate, in combination a metal band, one end of which is adapted to pass into one of the openings and outwardly through the opening at one end of the said plate, the other end of said band being adapted to pass into the opening and be bent about the positioned band so that the two respective ends lie together.

Signed at Melbourne, Victoria, Australia, this 17th day of October, A. D. 1930.

RAGNOR WILHELM MONTÉN.
